UNITED STATES PATENT OFFICE.

HENRY JASPER GRIMM, OF QUINCY, ILLINOIS.

DESIGN FOR A FEED-COOKER.

SPECIFICATION forming part of Design No. 31,135, dated July 4, 1899.

Application filed June 6, 1899. Serial No. 719,617. Term of patent 14 years.

To all whom it may concern:

Be it known that I, HENRY JASPER GRIMM, of Quincy, Illinois, have invented and produced a new and original Design for a Feed-Cooker, of which the following is a specification, reference being had to the accompanying drawings.

In the drawings, Figure 1 is a perspective view of the invention. Fig. 2 is a longitudinal section, and Fig. 3 is a cross-section.

The leading feature of the invention relates to the configuration and shape of the cooker, and it comprises, as shown in Fig. 3, a half-round receptacle A, supported on vertical walls B, so that in end elevation the cooker is

of reduced width in this lower part, with its upper walls flaring outwardly. The front and rear walls, as at C D, are vertical, but they conform in configuration to the cross-section of the body.

What I claim is—

The design for a feed-cooker as herein shown and described.

In testimony whereof I affix my signature in presence of two witnesses.

HENRY JASPER GRIMM.

Witnesses:

GEO. A. BINKERT,
WM. J. BINKERT.
